United States Patent Office

Des. 177,684
Patented May 15, 1956

177,684

THERMOSTAT HOUSING

Homer E. Malone, Milwaukee, Wis., assignor, by mesne assignments, to General Controls Co., a corporation of California

Application March 10, 1954, Serial No. 29,448

Term of patent 14 years

(Cl. D52—7)

Figure 1 is a front view of a thermostat housing, showing my new design.

Figure 2 is a top plan view.

I claim:

The ornamental design for a thermostat housing, substantially as shown.
